US0D1066473S

(12) **United States Design Patent** (10) **Patent No.:** **US D1,066,473 S**
(45) **Date of Patent:** **** Mar. 11, 2025**

(54) **FRAME FOR EYEGLASSES**

(71) Applicant: **Warby Parker Inc.**, New York, NY (US)

(72) Inventors: **Adam Mendelsohn**, New York, NY (US); **Bo Zhao**, New York, NY (US)

(73) Assignee: **Warby Parker Inc.**, New York, NY (US)

(**) Term: **15 Years**

(21) Appl. No.: **29/720,540**

(22) Filed: **Jan. 14, 2020**

(51) **LOC (15) Cl.** **16-06**

(52) **U.S. Cl.**

USPC **D16/334**

(57) **CLAIM**

The ornamental design for frame for eyeglasses as shown and described.

DESCRIPTION

FIG. 1 is a perspective view of a frame for eyeglasses;
FIG. 2 is a front view thereof;
FIG. 3 is a back view thereof;
FIG. 4 is a right side view thereof;
FIG. 5 is a left side view thereof;
FIG. 6 is a top view thereof; and,
FIG. 7 is a bottom view thereof.
The broken lines represent unclaimed subject matter and form no part of the claimed design.

1 Claim, 5 Drawing Sheets
